UNITED STATES PATENT OFFICE.

LEONARD D. NILSON, OF WAYZATA, MINNESOTA, ASSIGNOR TO MARQUETTE MANUFACTURING COMPANY, OF ST. PAUL, MINNESOTA, A CORPORATION OF MINNESOTA.

CRANE.

Original application filed November 2, 1925, Serial No. 66,308. Divided and this application filed July 6, 1926. Serial No. 120,779.

This invention relates to new and useful improvements in cranes, and particularly to cranes of the portable type adapted to be mounted, for example, upon an automobile 5 truck, for wrecking purposes.

The present application is divisional of my application for cranes, Serial No. 66,308, filed November 2, 1925.

The main object of the invention is to 10 provide a crane having a guide sheave at the upper end, mounted to swivel, and arranged to be rotated to permit the removal of an intermediate portion of a chain without the removal of the sheave, and while 15 opposite ends of the chain remain attached to a hoisting drum and to the load, thus allowing a change from indirect to direct draft by the drum.

The feature of the invention resides also 20 in the detail construction of the swivel, including a split cylindrical socket member as a part of the boom frame, substantially axially tangent to the forward side of the chain-receiving portion of the drum, and 25 including forwardly projecting arms forming with the split portion, a slot, disposed in substantially parallel relation to the socket axis, and further including a split sleeve telescopically engaged and rotatable 30 in the socket, with the split as a slot also parallel with the socket axis and normally facing rearwardly in substantially diametrical relation to the socket slot, whereby the sleeve may be rotated and the slots made to 35 register on the forward side of the frame, to permit removal of the intermediate portion of a chain when the same is attached at opposite ends. This arrangement permits the crane to be used as a winch for 40 effecting a direct pull on the load, as when towing.

Advantages will be further set forth in the description of the drawings forming a part of this application, and in said drawings:

Figure 1 is a perspective view of a crane having my improved swivel structure applied thereto, in certain relation to a winding drum;

Figure 2 is an enlarged detail sectional view showing the general construction of the swivel head at the upper end of the boom;

Figure 3 is a detail section corresponding

to Figure 2, showing how the lifting chain 55 or cable is disconnected from the guide sheave at the upper end of the boom, at the forward side of the boom and of the chain-receiving portion of the drum; and

Figure 4 is a plan section on line 4-4 of Figure 2.

For purposes of illustration, a crane has been shown comprising lower parallel supporting members 1, boom members 2 pivoted at the lower ends to the support members, and held at their upper ends by a casting 5, as one portion of my improved swivel construction. This element 5 provides a split cylindrical socket member 6, substantially axially tangent to the forward 65 side of the chain-receiving portion 15 of a winding drum 14, suitably held in bearings 70 adjacent the lower end of the boom, and adapted for operation in any well-known 75 manner. Extending rearwardly of the cylindrical portion 6 of the element 5 are ears 7, between which are connected the upper ends of adjustably extensible brace members 8. The cylindrical portion has forwardly 80 extending spaced parallel arms 9, forming 85 with the split portion a slot disposed in substantially parallel relation with the socket axis. The outer ends of these arms are apertured as at 10 and a bolt 11 traverses these openings, and the openings at 90 the upper end of a clevis 13. The element 6 is properly secured by bolts 20 passing through lateral extensions 21 of the element 6.

Telescopically engaging within the socket 95 element 6 is a split sleeve adapted for rotation in a socket, and having upwardly extending spaced arms 30, between which is journaled a sheave 31, the back surface of the groove of said sheave being substantially 100 in alinement with the axis of rotation of said sleeve. The split of this sleeve, as a slot 32, is parallel with the socket axis, and, as shown in Figure 2, normally faces rearwardly in substantially diametrical relation to the socket slot 33, whereby by rotation of the sleeve, the slots can be made to 105 register on the forward side of the frame to permit removal of an intermediate portion of a chain 35 having one end connected to the drum and the other end engaged over the sheave, as for example, as shown in Figure 1. As illustrated, the chain passes

around a pulley 37 and has a hook 38 at its forward end engaged with a clevis 13, this being the normal connection when used for lifting purposes.

5 By means of the elongated openings, or slots, 32 and 33, the chain may be readily disconnected from the upper end of the boom, without the use of tools, when it is desired to obtain a direct pull from the 10 drum, as shown in dotted lines in Figure 1, as when pulling a load upwardly over an embankment. To disconnect the chain it is only necessary to rotate the sleeve to a position shown in Figure 3, at which time 15 the slots 32 and 33 are in register on the forward side of the crane or boom. Under all normal conditions, the slots are out of register and, therefore, there is no possibility of accidental release of the chain during 20 a load-lifting operation.

Thus it will be seen that a crane equipped with a device contemplated by this invention may be quickly converted into a device for use as a winch or for lifting.

25 Having described my invention, what I claim is:

1. A winding apparatus comprising a chain and a drum whereon it is wound, a sheave for said chain, a supporting member 30 for said sheave having a cylindrical portion through which said chain passes, a head adapted to rotatably receive said cylindrical portion, said head and said cylindrical portion having elongated openings normally 35 oppositely arranged but adapted to be aligned to permit the chain to be passed therethrough to separate it from said sheave and supporting member.

2. A frame and a winding drum thereon, 40 said frame having a split cylindrical socket member, substantially axially tangent to the forward side of the chain-receiving portion of the drum, and having forwardly projecting arms, forming with the split portion a slot disposed in substantially parallel relation with the socket axis, and a split sleeve telescopically engaged and rotatable in the socket, and having a sheave journaled in its upper portion, with the split as a slot 45 parallel with the socket axis and normally facing rearwardly in substantial diametrical relation to the socket slot, whereby, by rotation of the sleeve, said slots can be made to register on the forward side of the frame, 50 to permit removal of an intermediate portion of a chain without removal of the sheave, and while the opposite ends of the chain remain attached to the drum and work, thus allowing a change from indirect 55 to direct draft by the drum, the arms of said socket having a cross-clamping bolt supporting a clevis for engagement by a chain hook.

3. A frame and a winding drum thereon, 60 said frame having a split cylindrical socket

member, substantially axially tangent to the forward side of the chain-receiving portion of the drum, and having forwardly projecting arms forming with the split portion a slot disposed in substantially parallel relation with the socket axis, and facing forwardly, and a split sleeve rotatable in the socket, and having a sheave journaled in its upper portion, with the split as a slot 70 parallel with the socket axis, and normally facing rearwardly in substantial diametrical relation to the socket slot, whereby, by rotation of the sleeve, said slots can be made to register on the forward side of the frame, 75 to permit removal of an intermediate portion of a chain without removal of the sheave, while the opposite ends of the chain remain attached to the drum and work, thus allowing a change from indirect to direct draft by the drum, or vice versa. 80

4. A support having a socket open at one side, and a sheave having a tubular extension rotatable in said socket, and open at that side opposite the sheave, the openings being normally out of register but adapted to be registered by rotation, the said sheave, when registration takes place, being opposite the point of registration. 85

5. A support having a socket open at one side, and a sheave having a tubular extension rotatably supported by gravity in said socket, and open at that side opposite the sheave, the openings being normally out of register but adapted to be registered by rotation, the said sheave, when registration takes place, being substantially opposite the point of registration. 95

6. In a device of the class described a drum, a support, a sheave having a tubular extension rotatable in the support, a flexible 105 draft element connected to the drum and passing through the tubular extension and engaged with the sheave, said support and tubular extension each having an opening, said openings normally positively held out of register as the result of draft on the sheave but adapted to be registered when draft is discontinued, to permit the draft element to be passed therethrough in direction of draft. 110

7. A winding apparatus comprising a drum, a support, a sheave having a tubular extension rotatable in the support, the sheave normally lying forwardly of the support in direction of draft, a flexible element 120 connecting the drum and passing through the tubular member and forwardly over the sheave, said support and tubular member having openings out of register during draft, but adapted to be registered to permit the draft element to be passed therethrough for separation from the sheave and supporting member, registration taking place when the sheave lies at a point substantially diametric to its draft position. 125

3. A device of the class described comprising a drum, a support, a sheave having a tubular element rotatable in the support, said support and tubular element having openings registerable, and a cable connected with the drum passing through the tubular element and about the sheave and adapted to be removed through the registered openings, the registration being effected when the sheave is moved laterally of the direction of draft. 10

In witness whereof, I have hereunto set my hand this 1st day of July, 1926.

LEONARD D. NILSON.
